R. C. BURNETT,
ATTACHMENT FOR INTERNAL COMBUSTION ENGINES.
APPLICATION FILED MAY 10, 1917.

1,323,827.

Patented Dec. 2, 1919.

R.C. Burnett
Inventor

Attorney

UNITED STATES PATENT OFFICE.

REX C. BURNETT, OF RALEIGH, ILLINOIS.

ATTACHMENT FOR INTERNAL-COMBUSTION ENGINES.

1,323,827.

Specification of Letters Patent.

Patented Dec. 2, 1919.

Application filed May 10, 1917. Serial No. 167,724.

To all whom it may concern:

Be it known that I, REX C. BURNETT, a citizen of the United States, and resident of Raleigh, in the county of Saline and State of Illinois, have invented certain new and useful Improvements in Attachments for Internal-Combustion Engines, of which the following is a specification.

This invention relates to new and useful improvements in attachments for internal combustion engines, and the primary object of the invention is to provide a humidifying attachment adapted to be connected with the carbureter of an internal combustion engine, by means of which steam and water are drawn from the radiator of the engine and delivered into said carbureter in a super-heated condition by action of the heat radiated from the exhaust of said engine.

Another object of the invention is to provide an attachment of this character which when applied to an internal combustion engine is adapted to increase the speed or power of the motor, effecting a saving of gasolene and oil, and preventing the deposit of carbon upon the interior of the cylinders and other parts thereby keeping the spark plugs and valves free from obstruction.

A still further object of the invention is to provide a simple and compact attachment of this character readily applicable to various types of internal combustion engines, which is adapted to utilize the heat radiated from the exhaust pipe to perform the super-heating function.

A still further object of the invention is to provide a device of this character which is easily and simply constructed, inexpensive to manufacture, and one which will be very efficient in operation.

With these and numerous other objects in view my invention consists of the novel features of construction, combination and arrangement of parts which will be herein referred to and more particularly pointed out in the specification and claims.

In the accompany drawings:

Figure 1 is a side elevation showing the device attached to the exhaust manifold of an internal combustion engine;

Fig. 2 is an enlarged vertical section on the line 2—2 of Fig. 1;

Fig. 3 is a detail perspective view of the super-heating chamber, and

Fig. 4 is a view of a slightly modified

form of the super-heating chamber applied to the exhaust pipe.

In describing my invention I shall refer to the drawings in which similar reference characters designate corresponding parts throughout the several views. In Fig. 1 I have shown the device attached to the conventional form of the exhaust manifold 1 of an internal combustion engine, the intake manifold being represented at 2 and associated with a conventional type of carbureter 3, these various parts being of the type generally used in internal combustion engines. The parts above enumerated form the parts to which the attachment is connected and with which it is associated to carry out the function to be hereinafter more fully described.

The numeral 4 designates a jacket of any desired shape, preferably cylindrical as shown in the accompanying drawings, and surrounding a portion of the exhaust pipe 1. This jacket is spaced from the wall of the pipe 1, as clearly shown in Fig. 2 of the drawings. Positioned within a jacket is the super-heating chamber 5, which is connected by a pipe 6 extending upwardly through the jacket 4 and adapted to be connected into the top of the radiator which is associated with internal combustion engines. The radiator is not shown, the same being of the conventional type ordinarily used in devices of this character. The jacket 4 is connected with the carbureter 3 by means of a pipe 7, said pipe being adapted to be formed in any desired shape, according to the type of engine to which the device is applied, in some instances it being necessary to make the same flexible.

The preferred type of super-heating chamber employed in this invention consists of a substantially rectangular hollow member, designated as a whole by the numeral 5, the chamber being curved arcuately, transversely, to conform to and closely engage the exhaust manifold and has its outer side provided with a plurality of perforations 8. The inner side of the chamber 5 is adapted to conform to the curvature of the exhaust pipe, and to be positioned on the same as clearly shown in Fig. 2 of the drawing. The super-heater 5 is provided with a pair of vent pipes 9 that extend from one end at the lowest point as clearly shown in Fig. 3, the said pipes being adapted to

carry off any unvaporized water from said chamber. The pipes 9 extend through one end of the jacket 4, and are carried to any suitable point for discharging the water.

5 In Fig. 4 is shown a slightly modified form of super-heating chamber which is designated by the numeral 10, the same comprising a zigzag pipe extending across the portion of the exhaust pipe 1 which is 10 inclosed by the jacket 4, said pipe having a plurality of spaced perforations 11 through which steam is adapted to escape into the jacket. The pipe extends through one end of the casing to carry off the unvaporized water, the other end of said pipe being connected with the pipe 6 which extends to the radiator of the engine.

In operation, it is obvious that the steam and water will be carried from the top of 20 the radiator or from the water tank, through the pipe 6 to the super-heating chamber

5. In this chamber the vapor will be superheated and the steam will be forced through the perforations 8, or 11 according to the form used, into the interior of the jacket 4. From the jacket 4, the superheated vapor is carried through the outlet pipe 7 to the carbureter 3. This attachment is very simple, and may be economically constructed, and owing to its extreme simplicity, the same is applicable to 30 various types of internal combustion engines, with practically no change to the structure thereof. The attachment will 35 greatly increase the efficiency or durability of the engine, as it will effect a saving of gasolene and oil, and remove carbon from the interior of the cylinders thereby keeping the spark plugs and valves clear of 40 the deposit of carbon. The pipe 10 in Fig. 4 may extend longitudinally in the jacket 4 if so desired.

From the foregoing description, taken in connection with the accompanying drawings, 45 the advantages of the construction and of the method of operation will be readily apparent to those skilled in the art to which the invention appertains, and

while I have described the principle of operation of the invention, together with the device which I now consider to be the best embodiment thereof, I desire to have it understood that the device shown is merely 50 illustrative, and that such changes may be made when desired as are within the scope 55 of the claims appended hereto.

Having fully described my invention, what I claim as new, and desire to secure by Letters Patent, is:

1. In combination with the exhaust manifold of an internal combustion engine, of a jacket entirely surrounding the exhaust manifold and closed at the ends and adapted to communicate with the carbureter, an arcuate chamber within the jacket and bearing at one side upon the exhaust manifold and with the other side perforated and spaced from the jacket, and an intake communicating with the chamber. 60

2. The combination with an internal combustion engine including the exhaust manifold and the carbureter, of a jacket entirely surrounding the exhaust manifold and closed at the ends and communicating with the carbureter, an arcuate distributing 75 chamber within the jacket and bearing at one side upon the exhaust manifold and spaced at the other side from the jacket, the spaced side of the chamber being perforated, and an intake communicating with 80 the chamber.

3. The combination with an internal combustion engine including the exhaust manifold and the carbureter, of a jacket entirely surrounding the exhaust manifold and 85 closed at the ends and communicating with the carbureter, a distributing chamber within the jacket and bearing at one side upon the exhaust manifold and spaced at the other side from the jacket, the spaced side of the chamber being perforated, and an intake communicating with the chamber. 90

In testimony whereof I affix my signature hereto.

REX C. BURNETT.
